UNITED STATES PATENT OFFICE.

LEONARD B. BUCHANAN, OF WOBURN, MASSACHUSETTS, ASSIGNOR TO THE CHASE-SHAWMUT COMPANY, OF BOSTON, MASSACHUSETTS, A CORPORATION OF MASSACHUSETTS.

RENEWABLE FUSE.

Application filed September 7, 1920. Serial No. 408,448.

To all whom it may concern:

Be it known that I, LEONARD B. BUCHANAN, a citizen of the United States, residing at Woburn, in the county of Middlesex and State of Massachusetts, have invented an Improvement in Renewable Fuses, of which the following is a specification.

This invention relates to a renewable enclosed electric fuse of the cartridge type especially designed for use with fuse terminals of the knife-blade type and has for its object to improve the construction, operation and ease of renewing the fusible element of the fuse.

15 Fig. 1 is a side elevation of a fuse embodying my invention.

Fig. 2 is a longitudinal sectional elevation of the fuse of Fig. 1.

Fig. 3 is an end view of the fuse.

20 Fig. 4 is a view similar to Fig. 3 but with the locking nut removed.

Fig. 5 is an end view of the fuse with the locking nut and end-cap removed.

Fig. 6 is a plan view of a knife-blade fuse 25 terminal.

Fig. 7 is a view of the inner end of the knife-blade plug, particularly illustrating the staggered arrangement of the gas passages therethrough.

30 Fig. 8 is an enlarged sectional detail of one end of the fuse with the fuse components in assembled position.

As here shown, the fuse comprises the usual tubular enclosing casing 10 of insulating material having the exteriorly threaded 35 ferrules 11-11 on its ends. A thin metal ring 12 is received within the casing at each end and is formed with two internal, diametrically-opposed struck-out portions or 40 projections 12' which extend longitudinally within the casing for a substantial distance and form internal guides adapted to be engaged by plugs forming parts of the contact blades and prevent rotation thereof. Said 45 rings and ferrules may be secured to the casing by the rivets 11' passed through all of said components. The fusible element is extended longitudinally within the casing and includes the fuse strip 13 of zinc or other 50 appropriate material and the contact blades 14 renewably secured at its ends by the bolts 15.

Said contact blades are formed of strips, preferably of copper, having reduced end-

portions 14' to which the ends of the fuse strip are secured. An exteriorly threaded plug is received on and preferably permanently secured to each contact blade at the middle thereof. Said plug has the threaded body-portion 16 and the enlarged annular flanged inner end-portion 17 adapted slidably to be received within the ring 12 and diametrically opposed peripheral notches or guide-ways 17' are formed in the periphery of said end-portion adapted to receive the guides 12' of said rings 12 whereby the plug and its contact blade will be retained against rotation in said casing. Said plug is formed with the outer end wall 18 having the elongated slot 19 therethrough and the reduced end portion 14' of the contact blade is extended therethrough up to the shoulder formed at the junction of the reduced and outer portions of the contact blade. The contact blade may be a tight friction fit in 75 said slot in the end wall but preferably the plug is permanently secured on the blade by suitable means as by peening the walls of the slot into forcible engagement with the contact blade, or soldering.

The fuse is arranged to vent through said plugs. For this purpose the plug is formed with the interior recess 20 in its body-portion and the larger interior recess 21 in the end portion 17 thereof.

The outer end wall has two diametrically opposed apertures therethrough disposed at right angles to the slot 19 and serve as vents for the escape of gas from the casing. The interior recess 20 contains a body of suitable foraminous material 20', as steel wool, asbestos fibres, perforated metal discs, and the like which serves to divide the gas into a plurality of small streams and cools the gas. Said recess 20 is closed by the disc 24 which is forced within the recess 21 against the shoulder 22 and retained therein by friction and forms the inner end-wall of the plug. Said disc has the elongated slot 26 therethrough which is arranged in line with the corresponding slot 19 in the outer end wall; and the contact blade is also extended through said slot. This construction provides a rigid supporting structure for the blade.

A plurality of apertures 27 for gas are formed through said disc 24; and said apertures are staggered with relation to the cor-

80

100

105

responding apertures 18^a in the end-wall of the plug so that a circuitous gas passage through the plug is provided.

Internally threaded end-caps 28 are removably threaded on the end ferrules. Said caps have the end-walls 28^b which extend beyond the walls of the enclosing casing 10 and have the openings 28^b therein; and the threaded body-portions of the plugs extend through said openings. The enlarged inner end-portions of the plugs, however, are of too great a diameter to pass through the openings and consequently the end-caps retain the plugs and contact blades within the casing. Internally threaded locking-nut 29 are removably threaded on the extended body-portions of the plugs and serve to draw the inner ends 17 thereof against the inner faces of the end-walls of the end cap and lock them and their contact blades to the end-caps.

In assembling the fuse, the fusible element which includes the blades 14 is extended through the casing, and the guides 12^a of the casing are caused to engage the guide-ways 17^a of the plugs 16 of the contact blades. The end caps are then screwed on the ferrules and the locking nuts are screwed on the plugs; and the fusible element will thereby be locked to the casing against rotatable and longitudinal movement.

The construction herein shown provides large and strong parts which can readily be handled without tools and the fusible element is locked in the casing by the locking nuts after the end-caps are on; the locking members are in full view; and the blades are very firmly held in position.

The dimension, numbers and arrangement of the recesses in the end plugs and also the amount and nature of the cooling material therein contained will be governed according to the capacity of the fuse and the service on which it is to be used.

45 The arrangement shown is very convenient in providing any desired character of vent; and the venting will not be affected by the subsequent re-loading of the fuse by the user and the joint between the plug and end cap can be made practically gas tight.

I claim:

1. In a renewable electric fuse, the combination of a tubular enclosing casing, an exteriorly-threaded ferrule received on its end, said casing having internal guides in an end thereof, an end-cap removably received on said ferrule having an end-wall inwardly extended beyond the wall of the casing and an opening in its end-wall, a contact blade having a flanged portion with guide ways therein for the guides of the casing and engageable with the end-wall of the end-cap also having an externally threaded portion extended through the opening in the end-wall of the end-cap, and an internally threaded

locking-nut received on the threaded portion of said contact blade to draw and hold the flanged portion thereof firmly against the end-wall of said end-cap and thereby lock said contact blade to said end-cap. 70

2. A renewable electric fuse comprising the combination of a tubular enclosing casing, exteriorly threaded ferrules received on the ends of the casing, rings having inwardly-directed projections forming guides received in the ends of said casing, end-caps removably received on said ferrules having end-walls inwardly directed beyond the walls of the casing and openings in the end-walls, contact blades having enlarged flanged portions with guide ways therein for the guides of the casing and engageable with the end-walls of the end-caps and also having exteriorly threaded portions extended through the openings in the end-walls of said end-caps, and interiorly threaded locking-nuts received on said threaded portions to draw and hold said flanged-portions firmly against said end-walls of said end caps and thereby lock said contact plugs to said end caps. 90

3. A renewable electric fuse comprising the combination of a tubular enclosing casing, exteriorly threaded ferrules received on the ends of the casing, said casing having internal guides in its ends, end-caps removably received on said ferrules having end-walls inwardly extended beyond the wall of the casing and openings in the end-walls, contact blades, externally threaded plugs in which said blades are fixed having enlarged flanged end-portions with guide-ways therein for the guides of the casing and engageable with the end-walls of said end-caps, said exteriorly threaded portions of said plugs extended through the openings in the end-walls of said end-caps and exteriorly threaded locking-nuts received on said plugs to draw and hold the enlarged flanged portions thereof firmly against said end-walls of said end-caps and thereby lock said contact blades to said end-caps. 100

4. A renewable electric fuse having the combination of a tubular enclosing casing, exteriorly threaded ferrules received on the ends of the casing, rings having internal projections forming guides received in the ends of the casing, end-caps removably received on said ferrules having end-walls inwardly extended beyond the wall of the casing and openings in the end-walls, contact blades, exteriorly threaded plugs in which said blades are fixed having enlarged flanged-portions with guide-ways therein engaged by said guides and also by the end-walls of the end-caps, the threaded portions of said plugs extended through openings in the end-walls of said end-caps and interiorly threaded locking-nuts received on said plugs to draw and hold said flanged por- 110 120 125 130 135 140 145 150 155 160 165 170 175 180 185 190 195 200

tions thereof firmly against the end-walls of said end-caps and thereby lock said contact blades to said end-caps.

5. In an electric fuse, the combination of a tubular enclosing casing, an exteriorly threaded ferrule received on its end, said casing having internal guides in an end thereof, an end-cap removably received on said ferrule having an end-wall inwardly extended beyond the wall of the casing and an opening in its end-wall, a contact blade, a plug having an enlarged flanged end-portion with guide-ways therein for the guides of the casing, a reduced externally threaded body-portion, an interior recess in its body-portion and an outer end-wall with an elongated slot therein through which the contact blade is extended, a foraminous body of cooling material received in said recess, the end-wall of said plug having gas vents therein, a disc having an elongated slot through which said contact blade is extended and gas vents therein fixed in the inner end of said plug whereby to enclose said foraminous body within the openings in the end-wall of said end-cap and an internally threaded locking-nut received on said plug to draw and hold the flanged portion of said plug firmly in contact with the end-wall of said end-cap and lock the contact blade to said end-cap.

6. A renewable electric fuse having the combination of a tubular enclosing casing, exteriorly threaded ferrules received on the ends of the casing, rings having internal projections forming guides received in the ends of the casing, end-caps removably threaded on said ferrules having end-walls with openings therethrough, a fusible element comprising a fusible central portion and contact blades at each end arranged longitudinally within the casing, plug-portions fixed to said contact blades having enlarged inner ends too large to pass through the openings in the end-walls of said end-caps and exteriorly threaded portions extended through said openings, said enlarged portions of said plugs having guide-ways for said guides, and interiorly threaded locking nuts received on the threaded portion of said plugs to lock said contact blades in place with relation to said end-caps, said plugs having interior recesses and end-walls with gas passages therethrough, and bodies of foraminous material received in said recesses.

7. A renewable electric fuse having the combination of a tubular enclosing casing, exteriorly threaded ferrules received on the ends of the casing, rings having internal projections forming guides received in the ends of the casing, end-caps removably threaded on said ferrules having end-walls with openings therethrough, a fusible element comprising a fusible central portion and contact blades at each end arranged longitudinally within the casing, plug-portions fixed to said contact blades having enlarged inner ends too large to pass

through the openings in the end-walls of said end-caps and exteriorly threaded portions extended through said openings, said enlarged portions of said plugs having guide-ways for said guides, and interiorly threaded locking nuts received on the threaded portions of said plugs to lock said contact blades in place with relation to said end-caps, said plugs having vent passages therethrough and foraminous bodies contained in said passages.

8. A renewable electric fuse having the combination of a tubular enclosing casing, exteriorly threaded ferrules received on the ends of the casing, rings having internal projections forming guides received in the ends of the casing, end-caps removably threaded on said ferrules having end-walls with openings therethrough, a fusible element comprising a fusible central portion and contact blades at each end arranged longitudinally within the casing, plug portions fixed to said contact blades having enlarged inner ends too large to pass through the openings in the end-walls of said end caps and exteriorly threaded portions extended through said openings, said enlarged portions of said plugs having guide-ways for said guides, and interiorly threaded locking nuts received on the threaded portions of said plugs to lock said contact blades in place with relation to said end-caps, said plugs having interior recesses and end-walls with gas passages therethrough, and bodies of foraminous material received in said recesses.

9. A renewable electric fuse comprising a tubular enclosing casing, a knife-blade fuse terminal having an externally threaded portion, said casing and terminal having cooperating components to prevent rotation of the terminal within the casing, an end cap removably threaded on said casing engageable by said terminal to prevent outward axial movement of said terminal and a lock-nut removably threaded on the threaded portion of said terminal to lock said terminal and end cap together.

10. A renewable electric fuse comprising a tubular enclosing casing having an internally projecting end-portion, a fuse terminal, an externally threaded plug fixed thereon engageable with said end-portion, and a lock nut removably threaded on said plug to engage said end-portion to lock said terminal in said casing.

11. A renewable electric fuse comprising a tubular enclosing casing, a knife blade fuse terminal, said casing and blade having cooperating means to lock the blade in the casing against rotation, and other means including a lock nut removably threaded on the knife blade to lock said blade against axial movement in said casing.

12. A renewable electric fuse comprising

- 5 a tubular enclosing casing, a knife-blade
10 fuse terminal having an externally threaded
15 portion, said casing and terminal having
complementary portions engageable to re-
strain the terminal from rotary movement
20 and outward axial movement in the casing,
and a lock-nut removably threaded on the
threaded portion of said terminal engage-
able with said casing to lock said terminal
25 to said casing.
13. A fusible element for a renewable en-
closed electric fuse of the cartridge type com-
prising a fusible strip, knife-blade fuse ter-
minals removably attached to the ends of
30 said fusible strip, plugs fixed to said blades
having externally-threaded body-portions and
inner enlarged end-portions formed with
guide-ways, said plugs also having in-
35 ternal gas-cooling chambers and end-walls
with staggered gas passages therein and
foraminous bodies of gas-cooling material
40 received within said chambers.
14. A fusible element for a renewable en-
closed electric fuse of the cartridge type com-
prising a fusible strip, knife-blade fuse ter-
minals removably attached to the ends of
45 said fusible strip, plugs fixed to said blades
having externally threaded body-portions and
inner enlarged end-portions formed
15. A knife-blade fuse terminal for a re-
newable enclosed electric fuse of the cart-
ridge type having a plug through which said
50 knife-blade is passed and to which said plug
is permanently attached, said plug being
formed with an inner gas cooling chamber
and end-walls disposed on said knife blade
55 and formed with gas passages therethrough.
16. A knife-blade fuse terminal for a re-
newable enclosed electric fuse having a plug
through which said knife-blade is passed
and to which said plug is permanently at-
tached, said plug having an inner recess and
60 a perforated end wall integral with the body
of the plug, a perforated disc disposed on
said knife-blade in said plug-recess and
forming an end wall of said plug, and a fo-
raminous body received in said plug-recess.

In testimony whereof, I have signed my
name to this specification.

LEONARD B. BUCHANAN
